UNITED STATES PATENT OFFICE

GEORGE J. MEYER, OF MILWAUKEE, WISCONSIN, ASSIGNOR TO GEO. J. MEYER MANUFACTURING COMPANY, OF MILWAUKEE, WISCONSIN, A CORPORATION OF WISCONSIN

FILLING MACHINE

Application filed May 7, 1927. Serial No. 189,548.

The invention relates to bottle filling and capping machines.

An object of the invention is to provide a combination bottle filling and capping machine in which the bottles pass directly from the filling mechanism to the capping mechanism in a continuous uninterrupted movement.

Another object of the invention is to provide a machine of this character including continuously rotatable filling and capping mechanisms.

A further object is to provide a capping mechanism including a revoluble group of capping devices and common actuating means for depressing said capping devices one at a time as they successively come into operative position.

A further object is to provide a capping mechanism of this character in which the capping devices are each provided with a segment having a rolling contact with an actuating element.

A further object is to provide a capping mechanism including spring means for determining the proper crowning pressure and so arranged as to obtain a crowning pressure of substantially the same value for bottles which are longer or shorter than normal.

A further object is to provide a bottle filling mechanism including siphons which have their inlet ends extending into receptacles movable therewith for insuring full siphons at all times, notwithstanding the existence of slight leaks or the elevation of the siphon above the liquid level in the supply tank.

A further object of the invention is to provide a bottle filling and capping machine including simple but effective means for accurately locating the necks of the bottles in operative position.

A further object is to provide a bottle filling and capping machine having bottle feeding means including a yieldable side wall to prevent damage to the machine by jamming of bottles.

A further object is to provide a bottle filling and capping machine including a rotatable bottle-feeding star wheel and a plu-

rality of overlapping spring fingers for urging the bottles into the notches of the rotating star wheel.

The invention further consists in the several features hereinafter set forth and more particularly defined by the annexed claims.

In the accompanying drawings, Fig. 1 is a top plan view of a filling and capping machine embodying the invention;

Fig. 2 is a side elevation thereof, parts being broken away, and parts being shown in section, especially along the line 2-2 of Fig. 1;

Fig. 3 is a transverse sectional elevation of the machine taken along the line 3-3 of Fig. 1;

Fig. 4 is a detail sectional elevation of one of the bottle feeding star wheels and its drive;

Fig. 5 is a perspective detail view of a modified form of bottle neck holder;

Fig. 6 is a detail sectional elevation showing the mounting of the bottle neck holder of Fig. 5 and its relation to the filling siphon, and

Fig. 7 is a detail sectional elevation of the bottle neck holder shown in Fig. 2.

In these drawings, the numeral 10 designates a rectangular marginally flanged base plate which is supported from the floor on vertically adjustable jack pedestals 11. A rectangular platform 12 provided with depending marginal flanges 13 is supported above the base plate 10 in fixed position by pillars 14. A terraced channel 15 is formed in the upper surface of the platform 12 near and parallel to one edge to receive and guide therein the upper flight of a bottle conveyor chain 16, the upper surface of which is substantially flush with the upper surface of the platform. The conveyor chain 16 may extend beyond opposite ends of the platform 12 any desired distance, and in the present instance the chain passes over sprockets 17 which are rotatably mounted in outrigger brackets 18 secured to the platform at the ends of the chain-receiving channel 15. The lower flight of the chain may be supported in a channel plate 15' suspended below the platform 12, as seen in Fig. 3. The upper flight of the

75

100

bottle conveyor chain 16 travels from left to right, as viewed in Fig. 1, the bottles 19 being placed on the chain at the left end and removed therefrom at the right end. The 5 sprocket 17 at the discharge end of the chain 16 is the propelling sprocket for the chain and is mounted on a shaft 20 carrying a driving sprocket 21 and journalled in the bracket 18 and in another bracket 22 spaced laterally 10 from the bracket 18.

A hollow column 23 is fixedly secured to the upper surface of the base plate 10 and has journalled therein a vertically disposed shaft 24 which carries at its upper end portion a 15 rotary circular table 25 and a superposed rotary liquid or syrup tank 26. The rotary circular table 25 has an axial thrust bearing on the upper end of the hollow column 23 and occupies a large circular opening in the platform 12, the upper surface of the table being substantially flush with the upper surface of the platform. The rotary table 25 has secured thereto a subjacent coaxial ring gear 27 which meshes with a pinion 28 (seen in 20 Fig. 3) secured to a vertical shaft 29 journalled in a bearing bracket 30 mounted on the base plate 10. The vertical shaft 29 carries a bevel gear 31 meshing with a bevel pinion 32 keyed at one end of a horizontal shaft 33, which is also journalled in the bearing bracket 30. The other end of the horizontal shaft 33 carries a gear wheel 34 which meshes with a laterally adjacent pinion 35 secured to one end of a horizontal shaft 36 journalled in bearing brackets 37, the other end of the shaft 36 carrying a pulley 38 which is driven by any suitable source of power, such as an electric motor. Through the above described 30 gearing the rotary table 25 and the superposed rotary liquid tank 26 are given a slow continuous rotation in the same direction and at the same rate of travel.

The liquid or syrup is conducted to the rotary tank 26 through a pipe 39 having a swivel connection 40 permitting the relative rotation of the tank and pipe, and a float-controlled valve 41 is provided in the pipe by means of which the liquid in the tank is maintained at a pre-determined level. A plurality 45 of bottle-filling siphons 42 are disposed radially about the rotary tank 26 and have their inner and longer legs within the tank. The outer and shorter leg of each siphon is provided with a depending discharge tube or 50 nozzle 43 having a side discharge opening 44 near its lower end capable of being covered by a valve sleeve 45, slidably mounted on the discharge tube and carrying a weight collar 46 at its upper end. Each siphon 42 is supported and guided for vertical movement on a rod 47 slidably extending through an annular flange 48 surrounding the tank 26 near its upper end, and also slidably extending through a guide bushing 49 passing through the rotary table 25. The lower end

of each rod 47 is carried at the free end of a lever 50 pivotally mounted on the under side of the rotary table 25. The free end of each lever 50 carries a roller 51 which is adapted to travel over a fixed cam 52 mounted on the table-supporting column 23, so that during the rotation of the table, the roller of each guide rod 47 rides up on the cam to elevate the attached siphon and then down on the cam to lower the siphon. The inner end of each siphon extends into and detachably carries, by means of a bayonet joint connection, a cup 53 which serves to keep the siphon filled even if there is a slight leakage of liquid from the siphon, or if the inner leg of the siphon rises above the level of the liquid in the tank.

The lower portion of the rotary syrup tank 26 carries a projecting annular flange 54 which may be integral with the tank, as shown, if desired, and this flange is provided with peripheral bottle-receiving notches 55 to form a star wheel, each notch being centered with the axis of one of the superposed siphon discharge tubes 43. An annular bottle neck holder 56 surrounds the upper portion of the rotary tank 26 and has peripheral notches 57 to accurately locate the bottles with respect to the siphons, the bottleneck holder being vertically adjustably attached to the tank to accommodate different heights of bottles. The flange 48 carries a depending cylindrical skirt 48' surrounding the tank 26 and having vertically extending slots 49' formed therein. The neck holder 56 includes a cylindrical flanged portion which fits about the skirt 48' for vertical sliding movement therewith and is releasably clamped thereto by bolts 50' passing through the slots 49'.

In the modified form of the invention 105 shown in Fig. 5 the bottle neck holder comprises a series of flanged arcuate segments 56' which are secured about the tank and which carry pivotally mounted neck-engaging forked levers or yokes 57' spring urged 110 upwardly to normal position. In the absence of bottles below the siphons the forked levers yield downwardly upon the descent of the weighted valve sleeves 45, thereby avoiding exposure of the siphon discharge 115 openings 44.

For the purpose of transferring bottles from the bottle conveyor chain 16 to the rotary filling table 25, a star wheel 58 is placed above the table between the conveyor chain and filling table and is provided with peripheral bottle-receiving notches 59. The star wheel is secured to the upper end of a vertical shaft 60 journalled in a bearing 61 and carrying a sprocket 62 at its lower end, the sprocket being driven by pins 63 depending from the rotary filling table 25, so that the table and star wheel are co-ordinated in rotation. The star wheel is partially surrounded by a series of laterally-acting arcu- 125 130

ate spring fingers 64 mounted on the inner face of an arcuate supporting plate 65 and engaging the bottles to urge them into the notches 59 of the star wheel. The free end of each finger 64 projects in the direction of rotation of the star wheel 58 and overlaps the fixed end of the next spring finger.

Guide walls 66 are placed on opposite sides of the incoming portion of the bottle conveyor or chain 16, and those portions of the guide walls adjacent the star wheel 58 are disposed angularly to direct the bottles into the star wheel. A deflector block 67, which forms a continuation of the outer guide wall 66 adjacent the star wheel, is mounted on a horizontally movable hinge plate 68 sprung urged inwardly so that the deflector block may yield outwardly under abnormal pressure to the dotted line position of Fig. 1, thereby constituting a safety gate which will prevent any jamming of bottles at the star wheel. The bottles entering from the star wheel onto the rotary filling table 25 and into the star wheel notches 55 are further guided by a finger 69 which insures retention of the bottles on the table at the time of leaving the star wheel.

A hollow column 70 is fixedly secured to the upper face of the base plate 10 and supports therein in splined relation for longitudinal sliding movement a vertical shaft-like pillar 71, the pillar having a threaded lower end portion 72 on which is screwed a hand wheel 73 whereby the pillar may be adjusted in elevation. A rotary table 74 surrounds and is journalled on an intermediate portion of the pillar 71, and is carried in axial thrust relation on the upper end of the column 70 through an interposed anti-friction bearing 75. The rotary table 74 is provided with a surrounding gear 76 meshing with the ring gear 27 of the rotary filling table 25, so that these tables are co-ordinated in rotation. The upper face of the table 74 carries a resilient bottle-receiving disk 74' which is substantially flush with the upper surface of the platform 12, there being a circular opening in the platform 12 slightly larger than the table to permit the free rotation of the table. A central sleeve 77 forming part of the table 74 projects upwardly above the disk 74' to surround the stationary pillar 71 on which it is journalled, the sleeve having a keyed connection with the lower portion of a capping head turret 78 which also has a bearing on the upper end portion of the stationary pillar 71. A bottle-receiving star wheel 77' is also keyed on the sleeve 77 in adjustable elevation above the table 74.

The capping head turret carries a concentric circular group of vertically movable spring-mounted capping heads or plungers 79 which are supplied with caps or crowns through a tube 80 connected to a hopper 81.

In the present instance, the upper end of each capping or crowning head 79 is provided with an arcuate segment 82, the segments for the several capping heads being arranged in a concentric circular group about the axis of the turret 78, as seen in Fig. 1. A lever 83 is disposed above the capping head turret with a portion immediately above the capping station and carries thereon a conical roller 84 which rolls on the plane horizontal upper surface of the segments 82. At its forward portion the lever 83 is guided for vertical movement in a guide fork 83', and at its rear end the lever is pivotally secured to one arm of a bell crank 85 which is pivotally mounted intermediate its ends on a standard 86 bolted to the platform 12. The end of the bell crank 85 pivotally carrying the lever 83 normally engages the upper end of an abutment 87 on the standard 86. A coil spring 88 adjusted to a suitable compression urges the other end of the bell crank 85 upwardly, so as to normally maintain the bell crank in engagement with the abutment 87. The free end of the lever 83 has pivotally secured thereto a depending reach rod 89, the lower end of which passes through the platform 12 and is guided for substantially vertical movement by its pivotal connection with the free end of a laterally-extending link 90 having its other end pivotally secured to the platform 12. A connecting rod 91 has its lower end mounted on a crank pin 92 on the gear wheel 34 and has its upper end pivotally secured to the lower end of the reach rod 89 at its pivotal junction with the free end of the link 90. By means of the above connection, the rotation of the gear wheel 34 causes the vertical reciprocation of the reach rod 89, which in turn rocks the lever 83 carrying the roller 84. On the downward movement of the reach rod 89, the roller 84 will depress the subjacent capping head segment 82 for effecting the capping operation.

In order to effect the transfer of filled bottles from the filling table 25 onto the capping table 74, a star wheel 93 is provided as seen in Fig. 1. The star wheel is secured to the upper end of a vertical shaft 94 which is driven in the proper direction, in the same manner as the transfer star wheel 59. For guiding the bottles in this transfer adjustably-mounted spring guide fingers 95 are provided, one of which serves to laterally engage the transferring bottles for urging them into the notches of the star wheel. To guide the bottles in their discharge from the capping table to the conveyor chain 16, spaced guide plates 96 are placed to form a bottle-receiving channel between them, as seen in Fig. 1, the guide plates 96 being preferably extended along the sides of the chain. The conveyor chain driving sprocket 22 is connected by a transmission chain 97 to a sprocket 98 on the shaft 33.

In operation, incoming empty bottles are placed on the loading end of the conveyor chain and are carried along the chain until they are deflected laterally into the star wheel 59 by the spring-mounted deflector block 67, which may yield if necessary should the bottles become jammed at this location. The bottles are thereupon carried around with the rotating star wheel 59 into the notches of which the bottles are urged by the several spring fingers 64. The rotating star wheel 59 slides the bottles onto the rotary filling table 25 and is so timed that the bottles are introduced into the notches 55 of the star wheel-forming flange 54 carried by the rotary liquid tank 26, the bottles being retained in the notches 55 during their initial movement by the spring finger 69. At the point of entry of the bottles onto the rotary filling table, the superposed siphons 42 are held elevated by the stationary cam 52 on which ride the rollers 51 of the siphon-supporting guide rods 47. As the table 25 rotates, the rollers 51 leave the stationary cam 52, thereby permitting the discharge tubes 43 of the siphons to descend into the bottles which have their necks properly located for this purpose by the notched neck-holder 56 or the pivoted yokes 57 of Fig. 5. When the discharge tube 43 of each siphon enters the bottle below, the weight 46 of the valve sleeve 45 stops at the bottle neck in order to expose the discharge opening 44 in the discharge tube as the discharge tube descends further into the bottle. Liquid or syrup from the rotary tank 26 is then introduced into the bottles by the siphons which are retained in the bottles for a time during the revolution of the rotary table 25. Before the bottles reach the star wheel 93, the siphons are withdrawn from the bottles by the riding of their rollers 51 upon the stationary cam 52, and the bottles in their further movement are transferred by the star wheel 93 onto the rotary capping table 74, the spring-guide fingers 95 insuring the proper travel of the bottles at this stage.

When the bottles pass onto the rotary capping table they enter the notches of the star wheel 77 carried by the upstanding sleeve 77 of the table in order to properly locate the bottles with respect to the superposed capping heads 79. As each capping head 79 passes under the conical roller 84 of the lever 83, the lever is pulled downwardly by its crank connection with the rotating gear wheel 34, and the roller 84 thereupon engages the arcuate segment 82 to depress the attached capping head for effecting the capping of the subjacent bottle. The capping operation takes place while the bottle is moving with the slowly rotating table 74 and during this interval the conical roller 84 rolls over the arcuate segment 82 on the capping head as the lever 83 is first depressed and then ele-

vated, the capping head being in its lowest position when the roller is at the central portion of the segment. During the next depression of the lever 83, the roller is acting on the succeeding arcuate segment which comes into position beneath the roller. The capped bottles are then guided off the capping table and onto the conveyor chain 16 by the guide walls 96, whereupon the bottles are conducted to the discharge end of the chain.

During the capping operation, the capping pressure is determined by the compression coil spring 88 acting on the lever 83 through the bell crank 85, and should the capping head meet with unusual resistance, the inner end of the lever 83 will yield on its fulcrum and rise above the abutment 87, thereby avoiding excessive crowning pressure. The spring 88 is compressed to an extent several times greater than the maximum spring action to obtain the initial crowning pressure, so that any extra length of bottles will only increase this pressure a small amount. For example: if the spring required a pressure of 50 pounds to move it one inch, it would have to be compressed eight inches to obtain an initial pressure of 400 pounds, and any additional compression would then be at the ratio of 50 pounds per inch. With this capping arrangement the capping pressure varies negligibly with longer and shorter bottles.

The siphon shown differs from the usual siphon in that the inner end lifts out of the liquid in the tank and the outer end is valved for shutting off the liquid. The cup or receptacle 53 holds a small quantity of liquid so as to prevent the loss of liquid from the siphon in case there should be a slight leak in the valve. In this manner, the outer end of the siphon is always full so that a slight leak at the discharge tube will not cause trouble, and the siphon is not disturbed by the elevation of the inner end of the siphon above the liquid or syrup in the tank, thereby permitting a lesser degree of submergence and consequently a lesser height of liquid in the tank than has been previously necessary. The neck-holder above the filling table accurately places the bottle necks in filling position, and similar neck-holders may be provided to properly locate the necks of the bottles below the capping heads.

In the filling and capping machine above described, the bottles pass directly from the filling mechanism to the capping mechanism, without interruption in their movement, thereby providing smooth and easy movement of the bottles in their passage through the machine and correspondingly smooth and easy operation of the filling and capping mechanisms. These features not only minimize wear and noise but also effect economies in power consumption, since the inertia effects attending intermittent bottle travel are largely eliminated.

What I claim as new and desire to secure by Letters Patent is:

1. The combination of a bottle carrier adapted to receive bottles thereon in upright position, bottle filling means including a bottle entering member and a valve member engageable with the bottle necks to permit filling, and a downwardly yieldable member laterally engageable with the neck portion of the bottles for locating them in operative position and adapted to be depressed by said valve member in the absence of a bottle below to prevent operation of said valve member.
- 15 2. The combination of a bottle carrier adapted to receive bottles thereon in upright position, bottle-filling devices each including a bottle-entering member and a valve member operatively engageable with a bottle neck to control filling, a support, and a downwardly yieldable member pivotally carried on said support and laterally engageable with the neck portion of a bottle for locating the bottle in operative position, said yieldable member being depressed by said valve member in the absence of a bottle below to prevent operation of said valve member.

In testimony whereof, I affix my signature.
GEORGE J. MEYER.
